FIG. 1

FIG. 2

INVENTOR:

Laura L. Artz

by

Pierre Barnes
ATTORNEY

UNITED STATES PATENT OFFICE.

LAURA L. ARTZ, OF SEATTLE, WASHINGTON.

DESIGN FOR A FIGURETTE.

59,450.

Specification for Design.

Patented Oct. 25, 1921.

Application filed May 4, 1921. Serial No. 466,702. Term of patent 3½ years.

To all whom it may concern:

Be it known that I, LAURA L. ARTZ, a citizen of the United States, residing at Seattle, in the county of King and State of Washington, have invented a new, original, and ornamental Design for a Figurette, of which the following is a specification, reference being had to the accompanying drawings, forming part thereof.

Figure 1 is a perspective view from the front, and Fig. 2 is a perspective view from the rear of a figurette, showing my new design.

I claim:

The ornamental design for a figurette, as shown.

Signed at Seattle, Washington, this 27th day of April, 1921.

LAURA L. ARTZ.

Witnesses:

PIERRE BARNES,
MARGARET G. SUPPLE.
